LOCKING DEVICES FOR TUBULAR LAMPS

Richard M. Runge, Meriden, Conn., assignor to
The Miller Company, Meriden, Conn., a corpora-
tion of Connecticut

Application January 15, 1941, Serial No. 374,449

8 Claims. (Cl. 173—328)

The present invention relates to locking devices for tubular lamps.

Tubular lamps such as fluorescent lamps now in common use are provided with two parallel pin terminals at the ends spaced standard distances apart and the pin terminals on the lamp are brought into engagement with corresponding fixed terminals on lamp sockets spaced apart so that the lamp can be passed between the sockets. These lamp sockets are usually mounted in a pendent position and the lamps inserted from underneath so that gravity cannot be relied upon in holding the lamps in place. Should the lamps for any reason twist or turn out of their normal working position in such a way as to permit separation from the contacts there is the possibility of the lamp loosening or dropping out from the socket.

The present invention contemplates lamp locking devices which can be readily inserted into place after the lamp has been placed in the socket, and these devices are then held in a fixed position such that the lamp cannot be twisted out of place an amount sufficient to loosen the grip on the contacts or to release the lamp. The lamp locking devices contemplated are small, inconspicuous devices, do not impair the efficiency of the lamp in any way and require no change whatever in the lamp. In one of the formations of construction to be described no change is required in the conventional lamp socket, while in the other form of construction a slight change is indicated.

The accompanying drawing shows, for purposes of illustrating the present invention, two of the many embodiments in which the invention may take form, it being understood that the drawing is illustrative of the invention rather than limiting the same.

In the drawing:

Figure 1 is a side elevational view of a fluorescent lamp carried in a typical lamp socket and provided with a lamp locking device carried by the lamp;

Figure 2 is a cross sectional view taken on the line 2—2 of Figure 1 with parts broken away to show interior construction of the socket;

Figure 3 is an elevational view taken from the left of Figure 1;

Figure 4 is a perspective view of the clip shown in Figures 1, 2 and 3;

Figure 5 is a view similar to Figure 1 illustrating a modified form of clip; and

Figure 6 is a section on the line 6—6 of Figure 5.

In Figures 1, 2 and 3 a typical fluorescent lamp socket is indicated at 10. It is adapted to be fixedly secured to a strap or other support 11 by a screw indicated at 12. A similar fluorescent lamp socket usually provided with a starter is mounted at the proper distance from the one indicated in the drawing, and a fluorescent lamp 13 is received between these sockets. The lamp has pin terminals 14, 14 at its opposite ends.

10 In the form of construction here illustrated the socket has two spring contacts 15, 15 and is provided with a straight passageway 16 through which the two pins 14, 14 may be inserted. The socket has arcuate passageways 17, 17 communicating with the entrance passageway 16 and the passageways and contacts are so located that when the two terminals 14, 14 of the lamp are inserted into the straight passageway as far as they will go and the lamp is given a turn of 90°, the pin terminals on the lamp traverse the arcuate passageways and engage and spread the contacts. These contacts are shaped so as to grip the terminals and provide proper electrical contact. The shape of these contacts and their engagement with the pin terminals on the lamp has heretofore been relied upon as the means of holding the lamp in the socket.

As fluorescent fixtures are mounted in locations subject to vibration there is the possibility 30 that the movable pins will creep along the spring contacts so that they gradually approach the straight passageway, and when this occurs it takes place at both ends of the lamp so that there is the possibility of the lamp falling out of the 35 socket. To overcome this difficulty a lamp locking device L is provided. As shown in Figures 1 to 4 this lamp locking device employs a spring clip, preferably made up of two pieces of spring metal indicated at 18, 18, secured to a plunger in 40 the form of a piece of fiber or other insulating material 19. These clips are of the right size to yieldingly grip the metal customarily used on the end of the fluorescent lamp. Different sized clips will be used with different sized lamps. The insulating plate or plunger 19 is offset from these metal clips an amount to permit it to enter the straight passageway 16 as illustrated in the drawing. When it is in place, as shown, the device is readily held on the lamp by the spring clip and the insulator closes off the straight passageway so that it is impossible for the lamp to twist out of its normal position an amount sufficient to permit its removal. One of these devices 55 is sufficient for each lamp, but, if desired, one

may be used on each end. When a lamp is to be removed the clip is readily withdrawn.

In the form of construction illustrated in Figures 5 and 6 the socket 20 is the same as the socket 10, except that the molded body from which it is made is provided with recesses 21, 21 on the side. The clip 22 is of a size to grip the sides of the socket and its ends are bent in, as indicated at 23, 23, to enter the recesses 21. A fiber plunger 24 is carried by the metal clip and enters the straight passageway in the same way as the plunger 19.

It is apparent that, within the scope of the invention modifications and different arrangements may be made other than is herein disclosed, and the present disclosure is illustrative merely, the invention comprehending all variations thereof.

What is claimed is:

1. In combination, a tubular lamp having parallel terminals at an end thereof, a supporting socket having a single straight passageway through which the two terminals may be inserted or removed, arcuate passageways on opposite sides of the straight passageway through which the terminals may be turned, and spring contacts to engage the terminals when turned from the entrance position and normally hold the lamp in the socket, a plunger insertible into the straight passageway after the insertion of the lamp terminals and extending across the first intersection of the straight and arcuate passageways to prevent turning of the lamp sufficiently to permit its removal, and means to removably hold the plunger in place.

2. The combination claimed in claim 1, wherein the plunger is of insulating material and extends across both intersections.

3. In combination, a tubular lamp having parallel terminals at an end thereof, a supporting socket having a single straight passageway through which the two terminals may be inserted or removed, arcuate passageways on opposite sides of the straight passageway through which the terminals may be turned, and spring contacts to engage the terminals when turned from the entrance position and normally hold the lamp in the socket, a plunger insertible into the straight passageway after the insertion of the lamp terminals and extending across the first intersection of the straight and arcuate passageways to prevent turning of the lamp sufficiently to permit its removal, and a spring clip

detachably secured to the lamp and carrying the plunger.

4. In combination, a tubular lamp having parallel terminals at an end thereof, a supporting socket having a single straight passageway through which the two terminals may be inserted or removed, arcuate passageways on opposite sides of the straight passageway through which the terminals may be turned, and spring contacts to engage the terminals when turned from the entrance position and normally hold the lamp in the socket, a plunger insertible into the straight passageway after the insertion of the lamp terminals and extending across the first intersection of the straight and arcuate passageways to prevent turning of the lamp sufficiently to permit its removal, and a spring clip detachably secured to the socket and carrying the plunger.

5. The combination with a tubular lamp having a pair of parallel terminals at the end, of a spring clip engaging the end of the lamp and carrying a thin insulating member extending between the terminals and terminating beyond the lamp axis at a distance substantially equal to the spacing of the terminals from the lamp axis.

6. A lamp locking device comprising a spring clip engagable with the end of a tubular lamp and an insulating plunger secured to the clip and extending radially inwardly at least to the clip axis, the plunger being disposed laterally of the clip.

7. The combination with a fluorescent lamp socket having an insulating body provided with a straight entrance passageway, two arcuate passageways on opposite sides of the entrance passageway and connecting with it at their ends, spring contacts in the arcuate passageways of an insulating plunger insertible into the entrance passageway for its entire length, and means for removably holding the plunger in place.

8. A device for locking the end of a tubular lamp having two parallel pin terminals into a lamp socket having cooperative contacts engageable and disengageable by lateral and angular movement about the lamp axis, comprising a laterally removable and replaceable spring clip adapted to grip the end of the lamp, and an insulating plunger disposed radially of the clip axis and laterally of the clip to pass by the end wall of the lamp and between interengaged terminals.

RICHARD M. RUNGE.
